UNITED STATES PATENT OFFICE.

ROBERT BAXTER ELDER, OF UNSANKINKO, CHOSEN, JAPAN, ASSIGNOR TO ANDREW DARWIN ELDER, OF DENVER, COLORADO.

HYDRAULIC CLASSIFIER.

Application filed June 20, 1918. Serial No. 240,997.

To all whom it may concern:

Be it known that I, ROBERT BAXTER ELDER, a citizen of the United States, and a resident of Unsankinko, Chosen, Japan, have ⁵ invented certain new and useful Improvements in Hydraulic Classifiers, of which the following is a specification.

My invention is an improvement in hydraulic classifiers, and has for its object to ¹⁰ provide a device of the character specified, wherein a teeter chamber is provided, arranged above hydraulic and discharge chambers, the latter communicating with the teeter chamber by a restricted opening and ¹⁵ the former by a number of openings, and wherein a stand pipe having an overflow is provided in connection with the discharge chamber.

A further object is to provide a means for ²⁰ introducing water into a teeter chamber in such a manner as to maintain even distribution of the water to all portions of the teeter chamber and so to prevent the formation of banks of sand in any portion ²⁵ thereof, and to maintain a uniform liquid bed of pulp over the entire teeter chamber area.

A further object is to provide a simple means for regulating the flow of water to the ³⁰ teeter chamber so that the regulation may be made and established correctly and thereafter will not be dependent on the judgment or guess of operating attendants.

A further object is to provide a device of ³⁵ the character specified wherein the discharge of the heavy classified pulp from the teeter chamber depends on the thickness and density of the bed of pulp in the teeter chamber.

In the drawings:

Figure 1 is a longitudinal section, showing the improvement applied to a single pocket classifier of the launder type;

Figure 2 is a section on the line 2—2 of Figure 1;

Figure 3 is a vertical section of the improvement applied as a cone classifier;

Figure 4 is a longitudinal section showing the improvement applied as a four spigot classifier;

Figure 5 is a front view of another embodiment of the invention;

Figure 6 is a plan view;

Figures 7, 8 and 9 are sections on the lines 7—7, 8—8 and 9—9, respectively, of Figure 6;

Figure 10 is a section on the line 10—10 of Figure 5.

In the embodiment of the invention shown in Figures 1 and 2, a casing is provided having its enclosing walls at the bottom perpendicular, as indicated at 1, and flaring above the perpendicular portion, as indicated at 2, where they connect with the launder 3. A partition 4 is arranged in the bottom of the casing, the said partition inclining ⁵⁵ downwardly from the inlet toward the outlet end of the casing, and the said partition is between the perpendicular walls of the casing.

Another partition 5 is arranged between ⁷⁰ the partition 4 and the bottom of the casing at the outlet end of the casing, and this partition 5 divides that portion of the casing below the partition 4 into two chambers, a hydraulic chamber 6 and a discharge ⁷⁵ chamber 7, and a delivery valve or spigot 8 leads from the discharge chamber. This discharge chamber communicates with the space in the casing above the partition which is the pulp chamber, and a series of openings 9 is provided in the partition 4 for furnishing a means of communication between the hydraulic chamber and the pulp chamber.

Drain valves 10 are provided in the bottom of the casing for draining the hydraulic chamber, and water is furnished to the chamber by a pipe 11 which is controlled by a valve 12. A stand pipe 13 is provided at one side of the casing, the said pipe extending from the bottom of the casing to above the top of the launder, the bottom of this pipe being connected with the discharge chamber, as shown, and this pipe has a discharge opening 14 above the pulp level ⁸⁵ through which the water may flow on to the pulp in the launder. A pipe 15 communicates with the bottom of the stand pipe by means of which water may be supplied to the pipe to maintain the water level at the ⁹⁰ overflow opening 14, and a valve 16 is arranged in the pipe for controlling the same.

In the embodiment of the invention shown in Figure 3 the casing has the portion 17 with perpendicular walls and the portion 18 with flaring walls, and the overflow launder 19 is arranged near the top of the casing in a manner to receive the overflow from the casing. A feed cone 20 is arranged centrally of the casing at the top, and the stand pipe 21 extends upwardly from near the bottom of the casing to above the top of the feed cone. Here the stand pipe is provided with a discharge spout 22 discharging into the cone, and with a supply pipe 23 for maintaining the level of water in the stand pipe. This pipe 23 is controlled by a valve 24 and the pulp is fed to the feed cone by a feed launder 25. A partition 26 is arranged near the bottom of the casing the said partition dividing the casing into an upper teeter chamber and a lower portion which is sub-divided by partition 27 into a hydraulic chamber and a discharge chamber, the lower end of the stand pipe communicating with the discharge chamber. The partition 26 inclines downwardly toward the center of the casing, and it is provided with openings 28 forming a communication between the teeter chamber and the hydraulic chamber. The discharge chamber communicates with the teeter chamber and a discharge valve 29 leads from the discharge chamber. Drain valves 30 are provided in the hydraulic chamber, and water is supplied by means of a pipe 31.

In the embodiment of the invention shown in Figure 4, the casing has the portion 31 with vertical walls and the portion 32 with flaring walls which connect with the launder 33. The lower portion of the casing is divided by vertical partitions 34 into four pockets, and an inclined partition 35 separates each pocket into a lower portion and an upper portion. These partitions 35 incline downwardly toward the discharge end of the casing and a partition 36 separates each lower portion into a hydraulic chamber and a discharge chamber. The partitions 35 have openings 37 corresponding to the openings 9 and 28, and a discharge valve 38 leads from each discharge chamber. Each hydraulic chamber has drain valves 39, and a standpipe 40 leads upwardly from each discharge chamber to above the level of the top of the launder. These stand pipes 40 have overflow outlets 41 corresponding to the outlets 14 and 22, and it will be noticed from an inspection of Figure 4 that the said openings are of less height above the bottom of the casing at the discharge end of the launder than at the inlet end, that is, the stand pipe 40 at the inlet end has its overflow opening at a higher level than the remaining openings, and they are gradually stepped downwardly from the inlet to the outlet end of the casing.

Water is supplied by a water pipe 42 to the hydraulic chambers, each chamber having its supply independent of the other chamber.

The operation of all of the embodiments is the same, each being a hindered settling hydraulic classifier, for classifying crushed ore, preparatory to treating it on Wilfley tables or other concentrators designed to separate the valuable minerals from the gangue. The device consists essentially of the following parts, namely, a teeter chamber wherein the ore pulp is thickened to a condition of hindered settling, and this condition maintained; second, means for bringing the unclassified pulp over the teeter chamber in order that the ore particles may have a chance to sink into the teetering mass or be crowded out by heavier particles, as the case may be, with means for carrying away the lighter portions of the pulp which could not sink into the teeter chamber; third, means for introducing hydraulic water into the teeter chamber through small holes in the bottom thereof and in such a way as to maintain uniform hindered settling conditions over the entire area of the teeter chamber, and as not to allow particles of ore to settle out of the teeter chamber against the incoming hydraulic water; fourth, means for discharging the heavy classified pulp from the teeter chamber, at or near the bottom, and into a discharge chamber wherein the hydrostatic pressure is regulated independently of the hydraulic water which does the classifying; fifth, means for maintaining constant or nearly so the hydraulic pressure in the discharge chamber; and, sixth, means for introducing water into the discharge chamber and independently of the water introduced into the teeter chamber.

The problem of making a successful hindered settling classifier may be resolved into two parts; first, to produce and maintain uniform hindered settling conditions over the entire teeter chamber area; second, to discharge the products of classification separate from each other and as fast as they are formed.

In order that there may be uniform hindered settling conditions over the entire area of the teeter chamber it is necessary that there be a slowly upward moving current of water uniform or nearly so over the entire area. The hydraulic water enters the teeter chamber from the hydraulic chamber through the constriction openings 9, 28 and 37 in the partition which separates these chambers, and as it enters the teeter chamber it is in the form of jets. These jets spread out as the water moves upward and mingle with the pulp, and the result is that a short distance above the bottom of the teeter chamber the hydraulic water is

diffused uniformly into the pulp and forms the desired slowly upward moving current of water practically uniform over the entire teeter chamber area. The lowest portion of the teeter chamber space is not available for the sorting action of the classification but is necessary to allow the jets of water to become mingled with the body of the pulp. The depth required to accomplish this depends on the distance between the constriction openings and the velocity of the water in the jets. The nearer the holes are placed and the smaller the velocity of the incoming water the less depth is required for the diffusion to take place.

The essential function of the constriction plate or partition which separates the teeter and hydraulic chambers is to maintain the even distribution of the hydraulic water over the teeter chamber area. This it does by offering to the flow of hydraulic water such a resistance that the inequalities tending to form in the weight of the pulp bed at different points have no appreciable effect on the flow of water. The bed just over and adjacent to the point where the heavy classified material is discharged from the teeter chamber tends to become lighter, since here it is continuously removed, and the bed just under the point where the unclassified pulp is fed to the teeter chamber tends to become heavier, as heavy ore particles are continuously added at this point. In passing from the hydraulic water chamber to the top of the pulp bed the hydraulic water meets with resistance first from the constriction plate and then from the pulp bed. The resistance offered by the constriction plate must be great enough so that slight variations in the resistance offered at different points in the pulp bed do not materially effect the distribution of water over the teeter chamber area, and at the same time it must not be so great that the velocity of the incoming jets is so great as to require an undue depth in the pulp bed before they become diffused into the pulp. When the resistance offered by the constriction plate is great enough to maintain the proper distribution of the hydraulic water, as described, the velocity of the incoming jets of water will be great enough so that no ore particle can settle through the constriction openings against the entering current of water.

The discharge of the heavy classified pulp is regulated by controlling the hydraulic pressure in the discharge chamber. In practice, if sufficient water is permitted to flow into the discharge chamber, so that a little overflows the top of the standing column or stand pipe the hydraulic pressure will be maintained practically constant at the opening between the teeter chamber and the discharge chamber and will be fixed by the

height of the column of water. The cross sectional area of the column and its connection must be large enough so that the friction head of a small amount of water passing through them will be negligible. 70

The height of the overflow of the column is then made such that the hydraulic pressure maintained at the opening between the teeter and discharge chambers is equal to the hydraulic pressure due to a column of pulp, the height of the teeter chamber and of the density desired to be maintained in the teeter chamber plus the column of less dense pulp above the top of the teeter chamber. The density of the pulp above the top of the teeter chamber will remain practically constant, so that it is evident that under the conditions described, whether there is a movement of liquid from the discharge chamber into the teeter chamber or in the opposite direction will depend on the density of the pulp in the teeter chamber. If this density exceeds the amount necessary to balance the constant hydraulic pressure in the discharge chamber, there will be a movement from the teeter chamber into the discharge chamber. The movement from the teeter chamber into the discharge chamber will thin the pulp in the teeter chamber until equilibrium is again restored. 85 The movement of the water into the teeter chamber from the discharge chamber will hinder the particles from leaving the teeter chamber so that the density of the pulp in the teeter chamber will be thereby increased, and this will continue until equilibrium is again restored. In this way the density of the pulp in the teeter chamber will be kept practically constant, provided only that the area of the opening between the teeter and the discharge chambers is equal to or less than the area through which the coarse ore particles in the pulp being treated will pass simply by free settling, and without a movement of liquid either way, and provided, also, that this opening is not so small but what a slight increase of density of the pulp will produce movement enough to discharge the pulp as fast as it is formed by the ore particles fed to the teeter chamber. 95 100 105 110 115

In practice, the area of this opening, that is, the opening between the teeter and discharge chambers, should be something less than the area which will discharge the particles by free settling, say, for instance, half such area. Then the density of the pulp in the teeter chamber will increase until a steady stream of pulp is discharged into the discharge chamber, at a velocity equal to twice the average free settling velocity of the particles. In this way the machine will carry one-half its rated load or a large overload, and still give perfect hindered settling, provided that the area of the teeter chamber is large enough for the overload. 120 125 130

The operation of all the embodiments is the same.

The pulp is maintained at a predetermined level, as shown by the dotted lines 5 in Figures 1, 2 and 4, and the lighter pulp passes away through the launder. The heavier pulp is held in the teeter chamber in a condition for hindered settling, by the up-flow of the water through the openings 10 9. A constant hydrostatic pressure is maintained in the discharge chamber and there will be a passage of the pulp into the discharge chamber if there is the proper density of pulp in the teeter chamber. If this 15 density exceeds the amount necessary to balance the pressure in the discharge chamber there will be movement from the teeter chamber into the discharge chamber, while if the density is less than the amount necessary to balance the pressure in the discharge chamber there will be movement in the opposite direction. From the discharge chamber the pulp passes through the valves 20 8, 29 and 38 for further treatment.

25 The embodiment of the invention shown in Figures 5 to 10, inclusive, is characterized by the addition of a feed water chamber arranged above the classifier and from which all the water used by the classifier is derived. In the said embodiment of the invention two discharge chambers 50 and 51 are provided, separated from each other by a partition 52, and the chamber 51 is separated from the waste chamber 53 by a partition 54 and from the chamber 53 leads a waste pipe 55. The water is fed into the feed water chamber 56 which is above the discharge chambers, and to which water is delivered from a pipe 57 having a valve 40 58 for controlling the flow of the water. Spigots 59 lead from the feed water chamber and deliver to pipes 60, which pass downward through the discharge chambers, delivering to the hydraulic chambers 61, one 45 of which is arranged beneath each pulp or teeter chamber 62, of which there are two, corresponding to the number of discharge chambers and number of hydraulic chambers. Each teeter or pulp chamber 62 is 50 separated from the adjacent hydraulic chamber by a partition 63 having openings for permitting the water to flow from the hydraulic chamber to the teeter or pulp chamber. The excess water from the feed 55 chamber 56 over and above that passing through the spigots 59, flows over the end 64 of the feed water chamber into a passage 65, which opens into a passage 66 communicating with the discharge chamber 50 through 60 an opening 67. Each discharge column or chamber communicates with the adjacent pulp chamber through an opening 68, whose extent may be varied by means of a valve 65 or gate 69, mounted to slide in guides 70 on the chamber wall. These ports or open-

ings 68 are adjacent to the pipes 60 which lead the feed water from the spigots to the hydraulic chambers. A screen 71 is arranged between the feed water chamber proper and the spigots, to prevent the passage of sediment. Spigots 72 lead from the bottom of the discharge chambers 50 and 51 to deliver the pulp, and each hydraulic chamber is provided with a drain pipe 73, normally closed by a cap 74. These caps 75 may be removed to drain the hydraulic chambers. As shown, the hydraulic chambers are casings arranged in the bottom of the pulp chambers, the top of each casing being perforated to form the perforate partition. Openings 75 are provided at each pulp chamber, each opening being closed by a transparent plate 76, as, for instance, a plate of glass, to permit the contents of the chamber to be inspected. 80 85

In operation, the water supplied to the feed water chamber 56 is in excess of that which can pass through the spigots 59, and the excess flows over the partition 64 through the passages 65 and 66 and the opening 67 into the first discharge chamber 50. The chamber 50 is the discharge column and discharge chamber regulating the discharge of pulp from the first or adjacent teeter chamber 62. The overflow from this discharge 90 column or chamber is by way of the partition 52 separating the discharge chambers, and the chamber 51 is the discharge column of the second teeter chamber. The water coming through the opening 67 supplies 100 what is needed for the spigot 72 of the chamber 50, the excess of water overflowing the partition 52, as above stated, for supplying the spigot 72 of the chamber 51, from which flows the pulp delivered by the said chamber 51 from the second teeter chamber 62. The final excess of water overflows the partition 54 and runs to waste through the pipe 55. 105

The essential function of the feed water 110 chamber 56 and the spigots 59 leading therefrom is to furnish a means whereby the amount of water running to the teeter chambers may be accurately adjusted to the correct amount when the classifier is first put 115 into use, and this amount of water may thereafter be continuously furnished to each teeter chamber without the necessity for readjusting the water except to see that the required level of water is maintained in 120 the feed water chamber. In the construction which I show, the level of the water in the feed water chamber is maintained at the desired point by providing the feed water chamber with an overflow, but it is 125 obvious that any means for maintaining this water level would be equally as effective, as, for instance, a feed water chamber having no overflow and having the valve 58 controlled by a float in the chamber 56, so that 130

- the water in the said chamber 56 would be maintained at a constant level. With this construction another water supply for the discharge chambers 50 and 51 would be provided. This construction would not be a departure from the spirit of my invention, but I prefer the construction which I show in the drawings as it requires only one water supply.
- 10 It will be noticed that the top of the pipe 60 is high enough above the level of the pulp in the pulp chambers, which is indicated by the dotted lines of Figures 9 and 10, so that the water may rise in the said pipe high enough to force itself into the teeter chamber against any bed of pulp which can form therein, and this insures at all times a constant feed of water to do the classifying, the amount being determined 20 by the size of the spigots 59 and the head of water maintained in the feed water chamber, and independent of the density of the pulp bed in the teeter chambers. The screen 25 71 prevents any solid matter from finding its way into the spigots and thence to the hydraulic water chambers, where it might stop the restricted openings in the partition 63.
- In use, the unclassified pulp is fed into the 30 extension 77 at the front of the classifier, from whence it flows into the first teeter chamber 62. The pulp rejected by the first teeter chamber flows to the second teeter chamber, passing over the partition 78 which 35 separates the two chambers, and the lightest particles which are rejected by the second teeter chamber are contained in the pulp which flows over the partition 79 between the second pulp chamber and the outlet 82.
- 40 I claim:
1. A device of the character specified, comprising a casing, an inclined transverse partition near the bottom of the casing, an approximately vertical partition between the transverse partition and the bottom, said partitions dividing the casing into an upper pulp or teeter chamber and lower hydraulic and discharge chambers, means for supplying water under pressure to the hydraulic chamber, a discharge valve for the discharge chamber, a stand pipe communicating with the discharge chamber and extending above the pulp level in the pulp chamber and having an overflow above the said level, 50 the discharge chamber communicating with the pulp chamber by a restricted opening, the inclined transverse partition having openings for permitting the water to flow from the hydraulic chamber to the pulp chamber, 55 and means for delivering pulp to the casing.
  2. In a device of the character specified, a pulp or teeter chamber, a hydraulic chamber below the pulp chamber and communicating therewith by restricted openings, a discharge chamber adjacent to the pulp 60 chamber and having a valved communication therewith, means for maintaining a predetermined hydrostatic pressure in the discharge chamber, a feed water chamber above the pulp chamber and communicating with the hydraulic chamber.
  3. In a device of the character described, a teeter chamber, a hydraulic chamber there beneath and separated therefrom by a partition through which highly restricted openings are formed, means for supplying water through the partition to the teeter chamber in such a quantity that a predetermined pressure head may be maintained across the partition to effect even distribution of the water to all parts of the teeter chamber, means for supplying unclassified pulp to the teeter chamber, means for regulating the discharge of classified pulp therefrom and means controlled by the changing of pulp density for regulating the discharge of pulp from the teeter chamber.
  4. In a device of the character described, a teeter chamber in all parts of which a uniform hindered settling bed of pulp is maintained by water entering the teeter chamber through numerous restricted openings in the bottom thereof and under sufficient pressure to overcome the tendency of the pulp to form a bank or solid mass upon the bottom of the teeter chamber, and means in connection therewith and controlled by the changing of the pulp density, whereby the discharge of the heavy classified portion of the pulp will be effected.
  5. In a device of the character specified, a teeter chamber, means for supplying hydraulic water to produce hindered settling classification therein, means for maintaining the even distribution of the hydraulic water over the teeter chamber area by forcing it to enter the teeter chamber through numerous small openings distributed over the bottom of the teeter chamber, the said openings being so restricted that they form enough resistance to the passage of the water that the distribution of the water is thereby maintained regardless of slight inequalities in the weight of the pulp bed at different points in the teeter chamber, and means in connection therewith and controlled by the changing of the pulp density for regulating the discharge of the heavy classified portion of the pulp therefrom.
  6. In a device of the character specified, a teeter chamber, a discharge chamber with which the teeter chamber communicates by a restricted opening, means for supplying water under pressure to the bottom of the teeter chamber to produce hindered settling classification therein, a stand pipe communicating with the discharge chamber and extending above the pulp level in the pulp chamber and having an overflow above the pulp level, and means for removing the

heavy classified material from the discharge chamber otherwise than through the stand pipe connected thereto.

7. In a device of the character specified, 5 a series of pulp chambers, a hydraulic chamber below each pulp chamber and communicating therewith by restricted openings, a discharge column adjacent to each pulp chamber and having a valved communication therewith, a common feed water chamber communicating with each hydraulic chamber, said feed water chamber having an overflow leading to the discharge column of the first teeter chamber, each discharge 10 column having an overflow leading to the succeeding discharge column.

8. In a device of the character specified, 20 a pulp or teeter chamber, a hydraulic chamber below the pulp chamber and communicating therewith by restricted openings, a discharge column adjacent to the pulp chamber and having a restricted communication therewith, a feed water chamber above the discharge chamber and communicating with 25 the hydraulic chamber, the feed water chamber having an overflow leading to the discharge column.

9. In a device of the character specified, 30 a pulp or teeter chamber, a hydraulic chamber below the pulp chamber and communicating therewith by restricted openings, a discharge column adjacent to the teeter chamber and having a valved communication therewith, a feed water chamber above 35 the discharge chamber and communicating with the hydraulic chamber, the feed water chamber having an overflow leading to the discharge column.

10. A device of the character specified, 40 comprising a casing having an upper pulp chamber and lower discharge and hydraulic chambers communicating with the pulp chamber, means for supplying water under pressure to the hydraulic chamber, a stand pipe communicating with the discharge chamber, having an overflow level above the level of the pulp in the pulp chamber and filled to this overflow level with nearly static clear water, and means for removing 45 the classified pulp from the discharge chamber otherwise than through the stand pipe.

11. In a device of the character specified, 55 a teeter chamber, a hydraulic chamber beneath the teeter chamber and communicating therewith by restricted openings, means for supplying water under pressure to the hydraulic chamber, a discharge chamber with which the teeter chamber communicates by a restricted opening, means for producing in the discharge chamber at the discharge opening a constant hydrostatic pressure greater than that of a column of

clear water equal in height to the vertical distance between the discharge opening and 65 the surface of the pulp in the teeter chamber.

12. In a hydraulic classifier, a pulp chamber provided with feed and overflow means and a perforated bottom, a hydraulic chamber communicating with the pulp chamber through said perforated bottom, and provided with a water feed, a discharge chamber in direct communication with said pulp chamber adjacent said perforated bottom, a 70 pressure column in communication with said discharge chamber and provided with an overflow above the level of the overflow of the pulp chamber, and a water feed to said pressure column independent of the 75 water feed to said hydraulic chamber.

13. In a hydraulic classifier, a pulp chamber provided with feed and overflow means, a hydraulic chamber communicating with the pulp chamber through a plurality of 80 small apertures in the bottom of the pulp chamber, a discharge chamber in communication with the pulp chamber adjacent its bottom, a pressure column in communication with the discharge chamber and provided with an overflow above the level of the overflow 85 of the pulp chamber, and independent water feeds to the hydraulic chamber and to the discharge chamber pressure column.

14. In a hydraulic classifier, a plurality of pulp chambers, each provided with feed and overflow means and a perforated bottom and a hydraulic chamber on the other side of the said perforated bottom provided 90 with water feed, a discharge chamber in communication with each pulp chamber, a pressure column in communication with each discharge chamber and provided with an overflow above the level of the overflow 95 of its pulp chamber, and water feed means to the pressure column independent of the water feed to the hydraulic chamber.

15. In a hydraulic classifier, a pulp chamber provided with feed and overflow means 100 and a perforated bottom, a hydraulic chamber on the other side of the perforated bottom and provided with water feed, a discharge chamber in communication with the pulp chamber, a pressure column in communication with the discharge chamber and provided with an overflow above the level of the overflow 105 of the pulp chamber overflow, and water feed means to the pressure column independent of the water feed to the hydraulic 110 chamber.
